(57) **CLAIM**

The design of a loudspeaker housing, as shown and described.

DESCRIPTION

FIG. 1 is a top, front and right side perspective view of a loudspeaker housing showing our new design;

FIG. 2 is a left side view thereof, the right side being a mirror image;

FIG. 3 is a front view thereof;

FIG. 4 is a bottom plan view thereof;

FIG. 5 is a top, front and right side perspective view of a second embodiment of our new design, being an array of four of the speakers shown in FIGS. 1–4;

FIG. 6 is a left side view thereof, the right side being a mirror image;

FIG. 7 is a front view thereof; and,

FIG. 8 is a bottom plan view thereof.

The side wall contours and the mounting and positioning hardware components are shown in broken lines for illustrative purposes only and form no part of the claimed design.
